VASE

Orville C. Hamon, Cedars, Okla.
(P.O. Box 813, Fort Smith, Ark.)

Filed Aug. 1, 1961, Ser. No. 66,152

Term of patent 14 years

(Cl. D29—28)

FIGURE 1 is a perspective view of a vase showing my new design;

FIGURE 2 is an elevational view thereof;

FIGURE 3 is a top plan view thereof; and

FIGURE 4 is a perspective view of another embodiment of my invention wherein the concave-convex bowl portion employs four symmetrically displaced prongs rather than three.

I claim:

The ornamental design for a vase, substantially as shown and described.
